UNITED STATES PATENT OFFICE.

CHARLES D. HEATON, JR., OF PROVIDENCE, RHODE ISLAND.

EXPLOSIVE-ENGINE.

1,005,969.

Specification of Letters Patent.

Patented Oct. 17, 1911.

Application filed June 22, 1910. Serial No. 568,318.

To all whom it may concern:

Be it known that I, CHARLES D. HEATON, Jr., a citizen of the United States, residing at Providence, in the county of Providence and State of Rhode Island, have invented a new and useful Improvement in Explosive-Engines, of which the following is a specification.

This invention relates to certain new and useful improvements in explosive engines.

The invention particularly relates to and resides in the rotary valve, which consists of a solid rod or shaft having cut-away portions for the purpose of controlling or governing the intake and the exhaust.

The object of the invention is to produce a valve of this character which will be efficient in operation and which will be possessed of great strength and longevity.

20 In the drawings: Figure 1 is a central vertical sectional view of a four-cylinder engine. Fig. 2 is a fragmentary transverse section of one of the cylinders and its piston. Fig. 3 is a fragmentary end elevation, and Fig. 4 is a detail perspective view of the rotary valve.

In the drawings, the engine casing is designated 1 and is formed with four cylinders 2 in which reciprocate the pistons 3, the latter being connected to the crank mechanism 4 by means of the piston rods 5. The upper ends of the cylinders 2 are formed with a valve seat 6 which extends from end to end of the casing 1 and through all of the cylinders 2. A valve 7 which is composed of an elongated solid rod or shaft is mounted in the valve seat 6 so as to rotate therein, and is formed with eight ports each port being of quadrant form in cross section. Four of the ports designated 8 in the drawings are inlet ports and the remaining four ports designated 9 are the outlet or exhaust ports. It will be seen by reference to the drawings that there is an exhaust port and an inlet port for each cylinder, said ports being disposed at right angles to each other. As shown in Fig. 2 of the drawings, the ports are formed by cut-away portions which are substantially semi-circular in cross section and which have bottoms which extend in a straight line transverse of the length of the valve 7, in order that when the valve is in

the position shown in Fig. 2 it will be closed and when turned at right angles to the position shown in Fig. 2, communication will be established between the interior of the cylinder and the exhaust or inlet pipes. As shown in the drawings, the top of the casing 1 is formed with integral hood-like extensions 10 which register with openings 11 which are cut through the top of the casing and are adapted to register with the valve openings 8 and 9 respectively of the valve.

As shown in Fig. 2, the valve seats 6 are formed in the top or outer end walls of the cylinders whereby the valve rod projects on opposite sides of said walls, the mouths of the ports 8 and 9 being of sufficient length so as to have their ends extend beyond said opposite sides of the cylinder end walls to thereby permit communication between the hood interiors and that of the cylinders. The inner ends of the hoods 10 terminate at the inner side of the valve seat 6, the tops of the hoods extending over the tops of the cylinders and the opposite ends thereof being directed downwardly.

The rotary valve is driven from the crank shaft 4 by means of any suitable type of gearing such for instance as that depicted in the drawings.

The relative speed of the crank shaft and valve is 2 to 1, so that the valve will be rotated so as to alternately bring the exhaust and inlet ports for each cylinder into register with the respective exhaust and inlet pipes 12 which are connected to the hoods 10.

It will be seen that since the valve shaft or rod is of solid cross section, it is possessed of great strength and increased longevity as compared with a hollow rotary valve.

Having thus described my invention, I claim as new and desire to secure by Letters Patent:—

In an engine, in combination with a plurality of cylinders, the outer end walls of the cylinders being formed with valve seats, a valve including a rod of solid cross section disposed in said seat and having portions projecting on opposite sides of said cylinder walls, said rod being formed with an inlet and an exhaust port for each cylinder, said ports being of substantial arc-shape in cross section and having mouths of sufficient

length so that the ends of the mouths extend beyond opposite sides of the cylinder end walls to establish communication between the cylinder interior and exterior and a casting for each valve port carried by the cylinders.

In testimony whereof I have signed my

name to this specification in the presence of two subscribing witnesses.

CHARLES D. HEATON, JR.
